COIN CONTROLLED MECHANISM

Guldbrand Guldbrandsen, St. Johnsbury, Vt., assignor to E. and T. Fairbanks and Company, St. Johnsbury, Vt., a corporation of Vermont

Application July 15, 1935, Serial No. 31,409

13 Claims. (Cl. 194—97)

This invention relates to improvements in coin-controlled mechanisms and more particularly to devices to co-operate in the operation of scale mechanism or other similar mechanism.

5 One object of the invention is to provide manually operated means to push a coin dropping from a coin chute, to successive operative stations, together with means for temporarily holding the coin at each station.

10 Another object is to provide automatically operating safety means in the initial path of the coin to prevent its removal from the coin chute for further use in operating the scale or other mechanism.

15 Another object is to provide an actuating bar, which is under control of the inserted coin and is adapted to actuate co-operating mechanism.

A further object is to provide means carried by the actuating bar for controlling and operating allied mechanism.

20 These and other objects and features of the invention will more fully appear in the following description and will be particularly pointed out in the appended claims.

25 A preferred embodiment of the invention is illustrated in the accompanying drawings, in which.—

Figure 1 is a vertical elevation of the inner side of the coin-controlled mechanism assembly 30 embodying my invention, showing it in co-operation with an associated mechanism.

Figure 2 is an enlarged fragmentary view of the upper end of the assembly, showing the coin at the receiving station R and operative station A.

Figure 3 is an enlarged fragmentary view of the assembly, showing the coin at the operative station B.

Figure 4 is an enlarged fragmentary view, 40 showing the coin at operative station C and in dotted outline at the discharging station D.

Figure 5 is an enlarged fragmentary view of the outer side of the assembly showing the actuating bar in its inoperative position together 45 with the counter and its control mechanism.

Referring to the drawings 1 designates a vertically disposed assembly plate having an angular upper end 2 and being attached to a base plate 3 by an angle iron 4. Mounted on the inner 50 side 5 of the assembly plate 1 are two upper and lower coin chute plates 6 and 7, which are held spaced from the assembly plate 1 by intervening spacers 8a and 9b respectively, forming thereby a two sectioned coin chute 10a and 10b 55 for a coin inserted at the upper end. In order

to advance a coin CN dropping from the coin receiving chute section 10a to successive operative stations A, B and C, a plunger or push rod 11 (Fig. 1) is slidably mounted on the inner side 5 of the assembly plate 1 in a slotted outer guide member 12, extending under an inner guide plate 13 and being disposed at an angle to the upper coin chute section 10a, with its inner end adjacent to the upper coin chute outlet 14. The inner end of the plunger 11 slides between the angular edge 15 of the outer spacer 8a and a spaced lower L-shaped guide plate 16, which is located below the inner guide plate 13 and is fastened with the guide plate 13 to the assembly plate 1, thereby forming a guideway for the plunger 11. 15

In order to return the plunger 11, after its operation, to its inoperative position it is provided with a retractile coiled spring 17, which has its inner end secured to the upturned tip of an offset arm 18 attached to the plunger 11, while 20 its outer end is secured to the outer guide member 12.

A safety catch 19 for preventing the removal of a coin dropping from the upper coin chute 10a to the receiving station R, is located below 25 the lower end 14 of the coin chute and comprises a catch bar 20, engaging and sliding on the edge of the outer spacer 9b of the lower coin chute plate 1, the spacer 9b being spaced back so as to form a channel 21 in which the catch bar 30 20 is adapted to slide. Moreover, the catch bar 20 is provided at its upper end with a notch 22 engaging in its extended position the stop arm 16a of the guide plate 16 and thereby limiting its upward movement, and an extended arm 23 35 leading therefrom and adapted to advance and engage the edge of a coin, when initially pushed by the plunger 11 from the first operative station A to station B. The safety catch bar 20 is also provided with a retractile coiled spring 24, which has its upper end secured to an offset lateral lug 25 extending from the lower coin chute plate 1 and its lower end to an angular flange 26 at the lower end of the catch bar 20, which permits the catch bar to yield and be depressed by the 40 coin as it is advanced from the receiving station R to the first operative station A. At the lower end of the catch bar 20 is an extended guide arm 27, which is adapted to engage a spaced stud 27a mounted in the assembly plate 1, while the 45 extended arm 23 at its upper end engages the inner edge of the lower guide plate arm 16a, by which means the catch bar 20 is guided during its entire movement.

50 Located at the inner side of the upper coin 55

55

shute outlet 14 and along the inclined edge 28 of the inner spacer 8a is an inclined coin guide plate 29 (Fig. 2) provided on its lower edge with two adjoining inwardly curved coin guide recesses 30 and 31, a depending projection 29a and an intervening depending coin control projection 32, the depending projections forming the operative stations A and C, and the recesses 30 and 31 forming the coin guide portions B and D, respectively, with which the coin in its travel under control of the plunger 11 is successively engaged as will be hereinafter noted. Pivotally mounted on the outer side 33 of the assembly plate 1 (Fig. 5) is an actuating arm 34 extending through a guide plate 35 at its outer end and carrying approximately midway thereof a laterally extending coin contactor stud 36 provided with a coin contactor roller 36a, extending through an inclined limit slot 37 in the assembly plate 1 and beyond the opposite side thereof and carrying on its free end an actuating roller 38.

The coin contactor roller 36a on the coin contactor stud 36 is engaged and depressed by the coin CN as it travels from station A to station B (Figs. 3 and 4) and thereby operates the actuating arm 34 as hereinafter described. A retractile coiled spring 39 is secured at one end in an opening 40 in an upright arm 41 attached to the actuating arm 34, and at the other end to the assembly plate 1, by which means the actuating arm 34 is withdrawn to its inoperative position as shown in Fig. 5. Moreover, the actuating arm 34 is also adapted during its movement to co-operate with and operate allied mechanisms, as described in the co-pending application referred to below, such for example, as a counter 42 (Fig. 5) for recording the number of persons operating the mechanism. The counter 42 is mounted above the actuating arm 34 on the inwardly inclined arm 43 of a bracket 44, attached to the assembly plate 1 and is provided with a control arm 45 pivotally connected at its upper end to the counter actuating arm 46 engaging at its stroke a stop stud 47. The counter is operated simultaneously by the coin, when it reaches station B at the midway stroke of the actuating arm 34 (Fig. 3). The counter control arm 45 at its lower end is provided with an elongated adjusting slot 48 co-operating with a stud 49 located at the upper end of the upright arm 41 carried by the actuating arm 34, whereby the upright arm 41 is permitted to move with the actuating arm 34 to its full stroke. A retractile coiled spring 50 for withdrawing the counter control bar 45 to its inoperative position (Fig. 5) is secured by its upper end in an opening in the control bar and has its lower end inserted in the same opening 40 in the upright arm 41 to which the coiled spring 39 of the actuating bar is connected.

In operating the coin-controlled mechanism a coin CN descending from the upper coin shute 10a reaches the receiving station R (Fig. 2), whence under urge of the plunger 11 the coin, first engaging at station A the outer end depending projection 29a of the coin guide plate 29, pushes down the safety catch 19 and upon reaching the coin control recess 30 at station B the safety catch is freed by the coin and under control of the retractile coiled spring 24 it is drawn upwardly so that its extended arm 23 will engage the edge of the coin and thus prevent its withdrawal. When the coin reaches station 75 B it also engages the coin contactor roller 36a

carried by the actuating arm 34 and depresses it to its midway stroke, while under continued urge of the plunger 11 the coin gradually depresses the coin contactor roller 36a and the arm 34, ultimately reaching the depending coin control projection 32 at station C, which serves to guide the coin downwardly and to cause it to exert increased pressure on the coin contactor roller 36a at this point, and thereby push the actuating arm 34 downwardly to its full stroke and operative position at station C (Fig. 4). After the coin has functioned to operate the actuating arm 34 at stations A, B and C, under further urge of the plunger 11 the coin is pushed around the coin control projection 32 to the coin control recess 31 at the coin ejecting station D, where the coin is freed from the coin contactor roller 36a, thereby releasing the actuating arm 34 and guided by the control recess 31 the coin is permitted to drop into the lower coin chute 10b and hence to the coin box (not shown).

The coin-controlled mechanism embodying the invention and herein described is adapted to co-operate with and actuate any suitable mechanism with which it will function, such as weighing scales and heart beat indicator scale mechanism. Therefore, for illustrative purposes the coin-controlled mechanism is shown in the drawings (Fig. 1) co-operating with and actuating through its actuating bar 34 the control mechanism of the heart beat indicator scale mechanism covered in the co-pending patent application of Alvah B. Jacobus and Harlan A. Hadley.

In the heart beat indicator mechanism referred to there is employed an electric switch control member 51, (Fig. 1) pivotally mounted above an electric spring switch 52, which controls the circuit to an electric lamp (not shown) supplying the light to the light beam projector (not shown). The control member 51 is provided with a rounded lateral lug 53, an enlarged lower weighted portion 54, both extending inwardly, and at the lower end with an insulated contactor tip 55 normally depressing, as shown in Fig. 1, the lower spring leaf 56 of the switch and thereby holding the switch open. The actuating arm 34 at the midway position of its downward stroke depresses the lateral lug 53 of the control member, thereby partially raising the control member, releasing the contactor tip 55 from the lower spring leaf 56 and thus closing the circuit. At the full stroke of the actuating arm 34 the switch control member 51 engaged by the actuating coin contactor roller 36a is raised higher so that a pin 57 carried thereon is engaged by a locking hook 58, which holds the switch control member 51 in its elevated position, as shown in dotted outline in Fig. 1, while the light beam is being projected and the heart beat mechanism operated. When the operator steps from the scale platform the switch control member 51 is released from the locking hook 58 by a tripping dog 59, carried by an arm 60 connected to the rack rod 61 of the indicator mechanism, and is permitted under control of the weighted portion 54 to return to its operative position (Fig. 1), depressing the lower spring leaf 56 of the switch and thereby shutting off the current to the electric lamp of the projection mechanism (not shown).

While I have shown a preferred embodiment of my invention it is evident that modification of the invention may be made that will come

within the scope thereof and, therefore, I do not desire to limit the invention to the exact form of construction shown and described herein.

I claim:—

5. 1. In coin controlled mechanism, a coin receiving shute, slidably mounted coin advancing means disposed at the outlet of the coin shute, a pivoted actuating arm provided with laterally extending coin contactor means and located below 10 the coin advancing means and the coin shute, and laterally extending coin control means provided with successive recesses and spaced depending projections disposed at the coin shute outlet and adapted to guide and control the advance movement of the coin under influence of 15 the coin advancing means by engaging the depending projections of the control means and contactor means so as to thereby operate the said actuating arm.
20. 2. In coin controlled mechanism a coin receiving shute, slidably mounted coin advancing means disposed at the outlet point thereof, spring actuated coin arresting means slidably mounted below the coin advancing means 25 and coin shute outlet for temporarily arresting the coin at the outlet point, a pivoted actuating arm provided with laterally extending coin contactor means and located below the coin advancing means and the coin shute, and successively 30 recessed coin control means provided with spaced depending projections adjacent to the outlet of the coin receiving shute and adapted to guide and control the advance movement of a coin so as to cause the coin under urge of the coin advancing 35 means by engaging successively the depending projections of the control means to thereby operate the said actuating arm.
3. In coin-controlled mechanism, a coin receiving shute, slidably mounted coin advancing means 40 disposed at the outer side of the coin shute outlet, inclined successively recessed coin control means having spaced projecting portions and extending laterally from the opposed inner side of the coin shute outlet, and a pivoted actuating arm provided with laterally extending control means and located below the coin advancing means, the coin control means being adapted to guide a coin under urge of the coin advancing means to the successive recessed and projecting portions 45 formed in the control means and constituting operative stations for the coin as it is advanced, whereby the coin is caused to engage and depress the said lateral control means of the actuating arm and render it operative.
50. 4. In coin-controlled mechanism, a coin receiving shute, slidably mounted coin advancing means disposed at one side of the outlet of the coin shute, a pivoted actuating arm provided with a laterally mounted coin contactor and disposed below the coin advancing means, inclined successively recessed coin control means having spaced projecting portions and extending laterally from the opposite side of the coin shute and adapted to guide a coin to the said coin contactor from the outlet of the coin shute to the successive recessed and intervening projecting portions constituting coin operative stations formed in the control means, spring actuated 55 safety catch means comprising a notched slideable catch bar adapted to engage the edge of the coin when being advanced to the said successive operative positions and thus prevent its withdrawal from the coin shute, and a stop member adapted to engage the notch in the said

catch bar, thereby limiting the advanced operative movement of the catch bar.

5. In coin-controlled mechanism, a coin receiving shute, slidably mounted coin advancing means disposed at one side of the outlet of the coin shute, inclined successively recessed coin control means having spaced projecting portions and extending laterally from the opposite side of the coin shute and adapted to guide a coin from the outlet of the coin shute to the successive recessed and projecting portions constituting coin operative stations formed in the control means, spring actuated safety catch means adapted to engage the edge of the coin when advanced to the successive operative portions and thus prevent its withdrawal from the coin shute, and means disposed below the said coin advancing means adapted to serve as a guide therefor and a stop for the safety catch means at its advanced operative position.

6. In a coin-controlled mechanism, a coin receiving shute, slidably mounted coin advancing means disposed at the outer side of the coin shute outlet, inclined successively recessed coin control means provided with spaced, depending, projecting portions and extending laterally from the inner side of the said coin shute outlet, an actuating arm provided with laterally extending control means and located below the coin advancing means, the coin control means being adapted to guide a coin under urge of the coin advancing means to the said successive recessed and projecting portions formed in the control means and constituting operative positions for the coin as it is advanced, whereby the coin is caused to engage the said control means and thereby depress the actuating arm and render it operative, and spring actuated means for retracting the actuating arm to its inoperative position.

7. In coin-controlled mechanism, an assembly plate, a coin receiving shute including a top plate attached to the assembly plate and held spaced therefrom by opposed spacers, the inner spacer having a beveled lower end, a plunger slidably mounted on the assembly plate in spaced inner and outer guide plates and angularly disposed with its inner end normally at the outer end of the outlet of the coin receiving shute, an inclined coin control guide plate disposed opposite to the inner end of the said plunger, means for guiding the inner end of the plunger including the said co-operating beveled lower end of the inner coin shute spacer and a lower guide plate, an inclined recessed coin control guide plate, and means for preventing the withdrawal of coins from the coin receiving shute comprising a safety catch slidably mounted below the outlet of the said shute and provided with an extended arm for engaging the lower edge of a coin coming from the shute while the upper edge of the coin is engaged by the said inclined coin control guide plate.

8. In coin-controlled mechanism, an assembly plate, a coin receiving shute attached to the assembly plate, a slidably mounted plunger disposed at the outlet of the coin receiving shute, a pivoted actuating arm disposed below the said plunger and shute and provided with a laterally mounted roller, and an inclined coin control guide plate, disposed at the shute outlet and opposite the inner end of the plunger, having its lower edge provided with successive recessed portions with an intervening projection, whereby under urge of the plunger a coin is moved from the first

recessed portion around the said projection, by which the coin is directed downwardly to engage the roller on the actuating arm and thus push down the actuating arm to its full operating stroke.

9. In coin-controlled mechanism, an assembly plate, a coin receiving shute attached to the assembly plate, a slidably mounted plunger disposed on the inner side of the assembly plate at the outlet of the coin receiving shute, a pivoted actuating arm provided with a laterally extending stud and disposed on the outer side of the assembly plate and below the plunger and coin receiving shute disposed on the inner side of the assembly plate, and inclined coin control and guide means comprising a recessed plate on the opposite side of the coin shute outlet provided with means for causing a coin coming from the coin shute and under urge of the plunger to be guided thereby so as to engage the said laterally extending stud and swing the actuating arm downwardly to its operating position.

10. In coin-controlled mechanism, an assembly plate, a coin receiving shute attached to the assembly plate, a slidably mounted plunger disposed at the outlet of the coin receiving shute, a pivoted actuating arm disposed below the said plunger and shute, and provided substantially midway thereof with a lateral stud extending through an inclined opening in the assembly plate and carrying a roller thereon, and means for actuating the said actuating arm comprising a recessed control plate disposed opposite the inner end of the plunger and adapted to cause a coin under urge of the plunger and engaging the control plate to press down the coin to engage the actuating arm roller and thus move the arm to its operative position.

11. In coin-controlled mechanism, an assembly plate, coin receiving and outlet shutes attached to the assembly plate and provided with spacers, a plunger slidably mounted on the assembly plate and angularly disposed with its inner end normally at the outlet of the coin receiving shute and sliding between a combined guide and stop plate and the lower end of the inner spacer of the coin receiving shute, and means for preventing the withdrawal of coins from the coin receiving shute comprising a resilient safety catch slidably

mounted below the outlet of the coin outlet shute and provided with notched upper and lower longitudinally extended arms, the upper extended arm in its operative movement being adapted to be guided by the stop plate and the lower extended arm by a spaced stud, while in its advanced operative position the notch of the upper arm is adapted to be engaged by the said stop plate and its movement thereby limited.

12. In coin-controlled mechanism, an assembly plate, a coin receiving shute attached to the assembly plate and provided with spacers, a plunger slidably mounted on the assembly plate and angularly disposed with its inner end normally at the outlet of the coin receiving shute and sliding between a combined guide and stop plate and the lower end of the coin receiving shute, and means for preventing the withdrawal of coins from the coin receiving shute comprising a safety catch slidably mounted below the outlet of the said shute and provided with notched upper and lower longitudinally extended arms, the upper extended arm being adapted in operation to engage the said stop plate by its notch in its advanced operative position, while the lower extended guide arm is adapted to be engaged on its upper edge by a spaced stud serving as a guide for the said arm, and a coiled spring for actuating the said safety catch attached to the lower end of the safety catch and the side of the shute plate.

13. In coin-controlled mechanism, a coin receiving chute, slidably mounted coin advancing means disposed at one side of the outlet of the coin chute, successive recessed coin control means provided with spaced, depending projections and positioned on the opposite side of the coin chute being adapted to guide a coin from the outlet of the coin chute to the successive recessed and projecting portions constituting respectively the first and second operating stations and a discharge station formed in the control means, and an actuating arm pivotally mounted below the coin advancing means and provided with a laterally extending contactor stud adapted to be engaged by the coin advanced thereto which at the same time is engaged by the depending projection at the second operative station and thereby the actuating arm is depressed and actuated.

GULDBRAND GULDBRANDSEN.
